UNITED STATES PATENT OFFICE.

JOHN THOMSON, OF NEW YORK, N. Y.

ELECTRIC ZINC-FURNACE WITH INTEGRAL CONDENSER.

1,080,863.

Specification of Letters Patent.

Patented Dec. 9, 1913.

Application filed January 2, 1912. Serial No. 739,789.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being made to the accompanying drawings, forming a part hereof.

This invention relates to the metallurgy of zinc, having for its object the production of zinc fumes by thermo-chemical reaction, and then condensing the fume to liquid metal.

The particular means for attaining the desired results, and such an elucidation of the general principles applicable thereto as seem necessary for a complete disclosure, will be pointed out in connection with the description of the accompanying drawings; which represent one form of embodiment of the invention.

25 Figure 1 is a transverse center section of the furnace, viewed either right or left, as A, A¹, of Fig. 2; Fig. 2 on the left hand side of its center line is a vertical longitudinal section as on either the line B, or B¹, 30 while that portion on the right hand side of its center line is a vertical longitudinal center section, as C, or C¹, of Fig. 1; and Fig. 3 is a partial top plan view, as on the horizontal planes D, D¹, of Fig. 1.

35 The class or kind of material particularly intended to be treated in this furnace, (but it is not necessarily restricted thereto) is either igneous oxid of zinc or roasted sulfids combined with carbon as the reagent, where- 40 by, when adequately heated substantially the following representative reaction ensues, namely: $ZnO + C = Zn + CO$. If pure ZnO and C are used, in precisely correct relative proportions, then the answer of the above 45 formula is an exact expression of the result, in that all of the charged material would be volatilized as zinc fume and monoxid of carbon, whence there would be no residue; but such conditions do not obtain in commercial practice in that more or 50 less of inert residual matter will remain, depending upon the purity of the materials employed, when the formula becomes, as stated, simply representative. Moreover,

the presence of residual matter is a cause of 55 difficulty in realizing a successful result.

The heat necessary for decomposing the charge is derived from an electric current passed through a "resistor" formed of rods, principally carbon, interposed between terminals, or as it is commonly termed, a "rod-resistor," which is so constructed and disposed that the charge is acted upon by radiant energy. Two of such resistors H, H¹, are preferably employed, each being inter- 60 65 polated between carbon connectors, as 5, to which the current is conducted by terminals, as 6, received from copper electrodes 7, 7¹. The connectors are set to the natural angle, 30° from the vertical, to which the staggered 70 rods conform, as shown in Fig. 2. These resistors may be electrified from separate circuits, or in parallel, or in series, as may be desired.

75 The resistors are preferably built of round rods, each superimposed series being somewhat shorter than the underlying, thereby forming a blunt wedge in transverse section, the narrower side up, as shown in Fig. 1 and on the left hand side of Fig. 3. The ends of 80 the lower series of rods rest on refractory supports, as 8. This leaves a large portion of the lower series of rods exposed, and it is from these, between the supports, that the heat is transmitted downwardly, by radiation. 85 The object of the wedge-like section, with the broader portion beneath, is to produce a greater current density along the horizontal zone from which the heat is exhausted by the charge. 90 A still further augmentation of current density may be effected by using graphite rods for one or a plurality of the lower series, while those above are of amorphous carbon.

95 If air or CO₂ is introduced or formed beneath the resistors, then the lowermost series of rods may either be formed from re-crystallized carborundum (SiC), or graphite or carbon rods may be coated with SiC; which 100 will not be decomposed by the agents named. Such rods will of course be somewhat non-conductive of electricity, but they will yet be rather good conductors of heat. The diminution of current therethrough will, however, be fully compensated by the use of an overlying series of graphite rods. Moreover, the space 9, within the three-sided re-

sistor casings 10, may be kept filled and under some pressure, with inert gas, thereby preventing the entrance of any pernicious agent liable to attack the carbon. The condenser J is disposed midway between the parallel sides of the resistor casings or along the longitudinal center of the furnace. Beneath each resistor is a hearth V in which is formed a shallow trough or sump 12 which serves the double purpose of receiving the charge, 13, and collecting the residue, as 14, whether the latter be liquid or in ash-like or sintered form, and may be removed accordingly, as denoted at 15 or 16, Fig. 2. 15. The spaces beneath the resistors will herein-after be referred to as the reaction chambers. In the refractory supports 8 a series of inner ports 17 and outer ports 18 are formed. The outer furnace walls 19 are built so as to 20 leave inner side galleries 20 open at their tops, and in these walls are also formed a series of openings or ports 21, in axial line with the ports 18. The composite charge, as P, is placed upon the tops of the resistor casings and into the aforesaid galleries. It will thus be perceived that it is simply necessary to stoke the charge material, as by means of bars, from the bottoms of the galleries, into and through the ports 18, thence 25 forcing it forward beneath the incandescent face of the resistor.

Igneous oxid of zinc, or roasted concentrates, mixed with broken or ground carbon (coke or coal) form an excellent seal against 30 the escape of volatilized matter, or the introduction of free air; hence, as the charge material is forced inwardly, from the bottoms of the galleries, and the stoking rod is withdrawn, its volume is automatically 35 replaced by the gravitating supply from above. Moreover, when a sufficient quantity is stoked into the reaction chamber the ports 18 may then be packed full, thereby reinforcing the seals. The material in these 40 ports will also become considerably pre-heated by conduction, which is a feature of importance in that the resistors are thus not subjected to sudden and extreme fluctuations in temperature as would be the case 45 if cold material were successively inserted. It is to be observed in this connection that the upper and outer portions of the resistor casing 10, 10^a, are shown as relatively thin. The thickness can, manifestly, be increased 50 or decreased at will and the refractory employed may be a good or a poor thermal conductor; yet, in any event, whatever heat is emitted therefrom will not be radiated to atmosphere but will be usefully absorbed 55 by the reserves of charge material. A contingent advantage of this condition is that any freely entrained air or moisture will be more or less driven off and dissipated to atmosphere. Finally the emission of heat 60 from the inner sides of the resistor casings

is precisely counterbalanced one against the other. Therefore, it can be conservatively stated that upward of 90% of the heat-emitting surfaces of the resistors are availed of for useful effect.

As the reaction proceeds, residue as 14 will be precipitated and collected upon the hearths, the charge floating or resting thereon until its removal becomes necessary. If good grades of igneous oxid and reaction 70 carbon are used, the accumulation of residue 75 will be slight and its withdrawal need only be effected at long intervals, whereas in the case of concentrates or ores the volume of residue or slag will be much greater and its 80 removal must be made more frequently. When any of such residue withdrawals are necessary the collected charge material in either of the reaction chambers may be quite exhausted—the reaction in the other 85 chamber proceeding normally—and if the residue, whether of a sintered non-fluid character or pasty, or fluid, is not sufficiently hot, its removal may be readily facilitated by temporarily increasing the temperature of 90 the resistor until the desired fluidity or disintegration of the inert ash is obtained.

As the heat from the resistors is radiated to the charge, it will be apparent that the closer the top of the charge is to the lower 95 faces of the resistors, the more effective and intense will be the reaction. This feature is realized to a unique extent in that the clear space through which the heat units must pass will usually be within a range of 100 from one to three inches. Again, the heat effect is of a roasting character and as a consequence of this the upper surface of the charge will continuously be the hotter and the greatest intensity of reaction will be 105 precisely upon the said surface. However, this does not mean that the reaction will proceed and the gaseous products be evolved at the temperature of the resistor itself, for as there is no confinement of the zinc fume 110 and monoxid of carbon they will immediately begin to pass off, if entirely unobstructed, as and when the top of the charge becomes heated to or about the temperature 115 of reaction. This initiatory temperature in the $ZnO+C$ reaction, begins at about 1900° F. This means that a very high temperature in the resistors is not required; therefore even if there is a certain confinement of the evolved fume and gas in the spaces between 120 the resistors and charge, as by obstruction to their flow through the condenser they would not acquire a higher temperature than is desirable or necessary to dissipate by secondary reaction any CO_2 which may have 125 been evolved.

The volatilized products of the reaction pass through the inner series of ports 17 into the upper free space 23 of the condenser, thence passing downwardly through open- 130

ings as 24, formed by a series of spaced longitudinal rods 25 and spaced transverse rods 26, the rods in alternate series being preferably set so that the rods in one set are located below the spaces between the rods in the other series, in other words, in a staggered relationship. These rods may preferably be of graphite or amorphous carbon. According to the foregoing conditions of assemblage of the rods, the fume and gas are necessarily caused to directly impinge from one series of openings upon another series of rods, thence being successively split and deflected according to the number of series employed.

The lowest series of rods 27 are set close together, thereby forming a chamber or channel 28 having exits therefrom at its ends as through the openings or ports 29. Beneath this lowest series of rods is the zinc receptacle 30. Thus the traverse of the fume and gas must follow the courses indicated by the flow-arrows, that is down through the staggered openings to the channel 28, thence right and left to the exits 29 therefrom, and then into the zinc receptacle at each end thereof, and finally passing right and left toward its center. But as the lowest series of rods are simply set side by side and as they are not ordinarily produced with accuracy, either as to diameters or straightness, there is thus a large number of narrow slits through which some of the fume and gas and nearly all of the zinc condensed above will pass; consequently the flow from the end ports 29 and along the zinc receptacle will virtually be through a series of showers of liquid zinc-drops, a condition which is conducive to condensation.

The battery of staggered rods is supported by plates 31 which rest upon the lowest series of rods and these in turn are supported by plates 32 which are immersed in the zinc bath R whose temperature is controlled by the underlying chamber S, either by natural radiation thereto or by forced circulation of heat or cold air. In this wise a constant and wide difference of temperature is maintained between the top and bottom of the condensing chamber, and the said difference of temperature is in constantly progressive increments from high to low. Under these conditions the rate of condensation may be very high and it can be more or less adapted to the rate of gaseous evolution at the resistors.

If the condensation is complete then only CO will remain and this is educted from the zinc chamber by right and left hand ports 33, 33^a, to right and left hand flues or chambers T, T^a, from whence the gas is delivered to atmosphere as by means of pipes 34, 34^a. But if the condensation is not complete within the zinc chamber then any residual fume will be precipitated as metal

or "blue-powder", or oxid, within the side chambers or the pipes. Under normal conditions the CO which enters the side chambers will have a temperature of say from 900° to 1100° F. and may perhaps maintain a temperature in the inner walls thereof of from say 500° to 600° F., which serves the useful purpose of conserving the heat in the superimposed hearths.

It may be necessary under certain conditions and possibly desirable in the bulk of cases, to apply a layer of broken carbon, as coke, 35, upon the upper series of condenser rods, also to provide terminals as 36 whereby electric current can be passed through this bed of carbon resistor either to preliminarily heat it or to maintain a certain temperature therein. Thus if any CO₂ is formed in the reaction chambers and reaches the condensing chamber, a secondary or "cleansing" reaction will necessarily ensue in passing through the bed resistor, whereby only "clean" fume and CO will enter the rod battery, and if no additional CO₂ or air thereafter reaches the lower portions of the condensing chamber all of the fume can be regained in the form of liquid zinc. The upper series of rods which come in contact with the coke may be of carborundum to prevent free conduction of current into the body of rods beneath.

When the secondary reaction is required the coke will need occasional renewals. To facilitate this the lower series of cover-tiles or slabs 37 is provided with ports or openings 38 and the overlying bricks may be advantageously cut to produce a wedge-like section 39. By removing the latter the openings are exposed through which coke may quickly be inserted and stoked to a uniform thickness.

As is denoted in Fig. 3, all of the brick work which incloses the resistors and condenser, as to the plane D, is readily removable, as for the inspection, repair or replacement of the underlying elements. The top of the condenser cover is preferably brought flush with that of the resistors, thereby forming a flat floor upon which a considerable quantity of reserve charge material may be stored. This also acts to produce a very perfect air seal of the jointed brick work above the condenser. Obviously any cross-sectional form of rods may be used in the condenser battery, such as square or hexagon, and the spacing may be variously modified as, for example, the slots may become progressively narrower toward the bottom series, or vice versa, or the diameters of the rods may be progressively increased or decreased, as may be desired. This method of cross-disposal and also the alternate staggering of the rods can be availed of to effect a vast number of impingements, deflections and tumblings of the fume and

gas in contact with a relatively immense superficial condensing surface on members having the best known characteristics for the withdrawal of stored heat and all of the above features coöperate to attract and coalesce the minute primary "mist-drops" into zinc-spheres of sensible dimensions which will subsequently roll off the rods and gravitate into the bath. Again, should portions of the condensing system become cold enough to chill the fume, say about 775° F., no air or CO₂ being present, then this product will not be the so-called "blue-powder" (oxidized) of commerce but congealed spheres of unoxidized metal which can be fused and run together in the bath.

In stoking the charge the best results are realized by systematically forcing the material through the ports into one reaction chamber and then following this after a certain interval at the other. Raking rods may also be introduced to form cross furrows or trenches. Consequently, any tendency on the part of the charge, beneath the resistors, to sinter, "cake", or "rust" may be prevented and any imprisoned fume and gas may be liberated. Then, too, the resistors may be operated under a nearly constant and also a high input of energy, which is a first requisite for their efficient performance.

The disposal of the condenser between two longitudinal resistors is a feature which is regarded of prime importance in that the heat insulation at its sides may be said to be practically perfect, thereby forcing all of the volatile products of the reaction and nearly all of the heat stored therein to flow together in a common downward direction, that is, to the zinc bath whose temperature is controllable. The reaction set up by the combination of ZnO + C + Heat is endothermic and is a function of temperature, of calories and of time acting upon a relatively highly concentrated or compact mass; but the volatilized products thereof (theoretically Zn + CO) in which the latent heat of vaporization are stored, are very voluminous. Consequently it is essential that the velocity of flow shall be low, which means a slight friction head, and that ample time shall be afforded for the absorption and conveyance away of the floating heat units. To take temperature out of a gas is inversely analogous, say, to imparting temperature to air. Hence the present system inversely follows in principle what has been abundantly proven as most effective in the recuperation of air for reverberatory furnaces; that is, the air to be heated is impelled or drawn through a system of open "checkered" bricks previously heated. From this illustration it may be clearly comprehended that the cross stacked and staggered rods can be arranged to obtain the direct impinge-

ments necessary to withdraw (as also to impart) heat and yet without such a velocity of flow as would defeat the function played by time and also produce such a "back pressure" as would interfere with and retard the primary reaction. 70

Another advantage of using compound resistors with an interposed condenser is that the furnace as a whole can readily be designed to approximate a square in plan, 75 wherein the outer radiating surface becomes a minimum, but it will be obvious that the furnace is an operative element if either of the resistors are omitted.

Various modifications might be indicated, 80 but these have been purposely omitted, resting upon the general statement that the invention as illustrated denotes a preferred embodiment of principles of construction which are not intended to be limited in 85 scope or application by the precise details shown in the drawings.

What I claim is:

1. In an electric zinc furnace, a rod-resistor resting upon side supports containing 90 transverse ports.

2. In an electric zinc furnace, a rod-resistor resting upon side supports containing transverse ports with an intervening trough or sump. 95

3. In an electric zinc furnace, a rod-resistor resting upon side supports, its lower face being exposed to an underlying trough or sump and its upper and side surfaces being incased. 100

4. An electric furnace having outer walls set to form a gallery or galleries extending along the outer side or sides, of an inclosed resistor, and ports in said walls in axial alinement with corresponding ports 105 in the resistor support or supports.

5. In an electric zinc furnace, an inclosed rod-resistor or resistors whose casing or casings are sheathed with the material to be charged. 110

6. An electric zinc furnace having a rod-resistor, open below and inclosed above, and a system of ports through which the charge is stoked into a space beneath the exposed lower face of said resistor. 115

7. An electric zinc furnace having a rod-resistor, open below and inclosed above, with a system of charge-stoking ports, and a vertical gallery arranged to supply fresh charging material. 120

8. An electric zinc furnace having a rod-resistor, open below and inclosed above, with a system of charge-stoking ports and a vertical gallery, the reserve charge material acting as a seal against the entry of air 125 to or the exit of vaporized products from the reaction chamber.

9. In an electric zinc furnace, a rod-resistor whose lower series of rods is exposed to the reaction chamber, the said rods or 130

the surfaces thereof being of a material immune to attack from air or dioxide of carbon.

10. An electric zinc furnace having a rod-resistor which has one layer or series of rods

5 relatively electrically non-conductive, another or second layer or layers of rods which are highly electrically conductive, such as graphite, and a third layer or layers of rods of lesser electrical conductivity, such as 10 amorphous carbon, the three layers being arranged in the order enumerated.

11. In an electric zinc furnace, a resistor formed by stacking several series of rods disposed transversely to the flow of the current, each series being shorter than the other, from the bottom up.

12. An electric zinc furnace having two rod resistors, each acting upon a separate charge, and an interposed condenser adapted to receive the volatilized products from both reaction chambers through a series of communicating ports.

13. In an electric zinc furnace, the combination with a resistor or resistors adapted to volatilize the charge, of a condensing chamber whose upper portion is free space into which the gaseous products of the reaction primarily flow, and an underlying battery of cross-stacked rods so dispersed as 30 to provide flow spaces.

14. A condenser comprising a battery of cross-stacked and staggered condensing rods and provided with a channel or chamber portion, the floor of which is formed of contiguous rods and into which portion the condensed and gaseous matter flow and pass to ports or openings at the right and left which lead to an underlying receptacle containing a bath of liquid metal.

40 15. In a condensing chamber, a battery of cross-stacked and staggered rods which are supported on one or more series of plates, the lower portions of at least part of said plates being immersed in a bath of 45 liquid metal.

16. In an electric zinc furnace a condenser interposed between parallel reaction chambers, the volatilized products of the reaction passing downwardly through the condenser, 50 a bath of liquid metal in the bottom of the condensing chamber and a chamber or flue beneath the bath whereby the temperature

of the said bath may be controlled according to the rate of evolution of the fume and gas.

55

17. In an electric zinc furnace, a condenser interposed between parallel reaction chambers and constructed to receive all of the volatilized products of the reaction which produce pass downwardly to a bath 60 of liquid metal in the condenser whose temperature is controllable by a circulation of air or other gaseous fluid in a chamber below the said bath.

18. In an electric zinc furnace, a condenser interposed between parallel reaction chambers and also between parallel chambers or flues situated beneath the reaction hearths, with connecting ports, whereby the residual gas will flow from the lower portion 70 of the condenser chamber into the said flues, from whence it may be conducted to atmosphere.

19. In an electric zinc furnace, a condenser having a battery of cross-stacked 75 rods, the upper series of which serves as a hearth to support a bed of broken carbon for effecting a secondary or "cleansing" reaction.

20. A condenser having a battery of cross-stacked rods upon the top of which is a broken bed of carbon interpolated between terminals, whereby the said bed may be electrically heated.

21. In an electric zinc furnace, a condenser having a horizontal broken bed of carbon, supported in the upper portion of the condenser chamber, and a series of coverable overhead ports through which renewal carbon may be introduced.

22. In an electric zinc furnace, a condenser interposed between inclosed resistors, a top or cover formed of removable tiles or bricks, and an overlying layer of charge material acting as a seal.

23. In an electric furnace an inclosed resistor having adjacent galleries at least partially formed by removable side walls.

This specification signed and witnessed this 31 day of December, A. D. 1912.
